AUTOMATIC SHUT-OFF FOR GAS BURNERS

Filed Jan. 23, 1928

John A. L. Peters
INVENTOR
BY Victor J. Evans

UNITED STATES PATENT OFFICE

JOHN A. L. DETERS, OF CHICAGO, ILLINOIS, ASSIGNOR TO ASSOCIATED ENGINEERS COMPANY, OF CHICAGO, ILLINOIS, A CORPORATION OF ILLINOIS

AUTOMATIC SHUT-OFF FOR GAS BURNERS

Application filed January 23, 1928. Serial No. 248,896.

This invention relates to certain novel improvements in automatic shut offs for gas burners and the like.

The salient object of my invention is to provide a shut off device for gas burners or the like which will automatically function to shut off the gas supply to a burner in the event the flame thereof is extinguished.

Another object of the invention is to provide a device of the foregoing character which will be arranged in such a manner that the burner may be used with or without the automatic feature above described.

Another object of the invention is to arrange the device in such a manner that it will embody indicating means in order that the user of the device may readily ascertain whether or not the device is arranged for automatic operation.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a plan view of a gas burner with which a preferred embodiment of my invention is associated;

Fig. 2 is a side elevational view of the device as illustrated in Fig. 1;

Fig. 3 is a sectional view taken substantially on the line 3—3 on Fig. 1 showing the valve in open position;

Fig. 4 is a sectional view taken substantially on the line 4—4 on Fig. 3; and

Fig. 5 is a perspective detail view depicting a sleeve employed in my device.

Referring to the drawings wherein the preferred embodiment of my invention is illustrated, 10 indicates a burner which in the present instance is removably mounted on a supporting rod 11 that is carried by the frame of the stove with which the burner is associated. The burner 10 includes a mixing chamber 12 which is connected to the main portion of the burner 10 by a supply pipe 13. The forward end of the mixing chamber 12 embodies the usual adjustable

air admitting arrangement 14 and has a central opening 15 thereon.

The gas supply pipe is indicated by 16 in the drawings and a suitable valve construction, generically indicated by 17 in the drawings is disposed between the supply pipe 16 and the mixing chamber 12. The valve structure 17 includes a body portion 18 which has an outwardly protruding portion 19 that is adapted to be mounted in the gas supply pipe 16. Diametrically opposed to the protruding portion 19 is a protruding portion 20 on which an adjustable cap 21 is mounted which is adapted to extend through the opening 15 in the arrangement 14.

A passage 22 extends through the portion 19 and a passage 23 extends through the portion 20 and these passages are adapted to be connected by the port 24 provided in the valve stem 25. A tapered bore 26 is provided in the body portion 18 and the tapered valve stem 25 is mounted therein. The valve stem 25 is reduced at its lower end portion and a nut 27 is screw threadedly mounted thereon which engages a protruding portion of the body member 18 and by tightening the nut 27 the valve stem 25 may be brought into wedging engagement with the tapered bore 26. The valve stem 25 is rotatable and thus the port 24 may be moved into or out of registration with the passages 22 and 23.

The bore 26 terminates in a boss 28 formed on the body portion 18 and an enlarged recess 29 is provided in this body portion 28. A pin 30 is mounted so as to have a portion thereof extending into the recess 29. A sleeve 31 is disposed around the valve stem 25 and has a slot 32 formed therein which is adapted to be disposed around the pin 30 when the sleeve 31 is disposed so as to have the lower end portion thereof resting in the recess 29. Opposite the boss 28, a hollow boss 33 is provided through which the reduced portion of the valve stem 25 extends. A spring 34 is disposed around the reduced portion of the valve stem 25 in the hollow portion of the boss 33 and one leg thereof is anchored in an opening in the walls of said boss as indicated at 35 in the drawings. A slot 36 is provided in the lower end portion of the stem 25 and

the opposite end of the spring 34 is anchored in this slot. This slot also causes expansion of this portion of the stem 25 so as to lock the nut 27 in position. The spring 34 acts on the 5 valve stem 25 so as to urge said valve stem in a direction such that the port 24 will be held out of registration with the passages 22 and 23 or particularly so as to hold the valve in closed position.

10 Adjacent the upper end of the valve stem 25, a tapered hole 37 is provided. A slot 38 is provided in the sleeve 31 and said slot and said opening are adapted to be disposed in registration. The valve operating handle includes a stem portion 39 on which the hand grip 40 is adapted to be mounted, said hand grip 40 being retained on said stem portion between the headed end thereof and the washer 41 is forced into engagement with an 15 end of said portion 40 by a nut 42. A washer 43 of suitable resilient material is disposed between the nut 42 and the sleeve 31. The threaded portion 44 of the stem 39 is adapted to be mounted in the tapped hole 37 by turning the stem portion 25 so as to bring opposite ends of the opening 37 into registration with the slot 38 and by inserting the portion 44 through said slot into said opening. It is apparent that the spring 34 may be wound 20 so as to embody various tensions.

At a point diametrically opposed to the juncture of the supply pipe 13 on the upper side of the burner 10, a suitable recess 45 is provided. A thermically extensible rod 46 is 25 provided which includes a right angularly extending portion 47 that is adapted to be extended into the recess 45. The rod 46 extends across the face of the burner 10 and is directed through a supporting sleeve 46' provided adjacent the forward edge of the burner. The forward end of the rod 46 is screw threaded as indicated at 48 and an interiorly threaded collar 49 is mounted thereon. The collar 49 is provided with an insulating ring 50 which is adapted to permit expeditious movement of the collar 49 even when the same is heated. Adjustably mounted at the forward end of the sleeve 49 is a resilient engaging button 51 which is adapted to be 30 adjusted along the sleeve 49 by means of the set screw 52.

Formed on the gripping portion 40 of the handle construction as by painting thereon is an indicating marker 53, the purpose of 35 which will be brought forth presently.

Normally the spring 34 tends to hold the valve closed. However when the valve is 40 manually opened by gripping the handle portion 40 so as to turn the valve stem 25 and thus bring the port 24 into registration with the passages 22 and 23 gas may be supplied to the burner 10 which will be ignited in the usual manner. Sufficient tension will be exerted between the washer 43 and the sleeve 31 45 to retain the handle 40 in various adjusted

positions, this tension being great enough to overcome the action of the spring 34. Under these conditions the marker 53 is disposed so as to be viewed in plan view as indicated in Fig. 1. Operation of the burner 10 will act to heat the rod 46 and cause thermal expansion thereof. This will cause the engaging button 51 to engage the juxtaposed portion of the sleeve 31 and this sleeve 31 is preferably made of resilient material. Therefore said sleeve will be pressed against said valve stem 25 and will tend to hold said valve stem against the action of the spring 34. After a predetermined period has elapsed which will afford sufficient time for the rod 46 to expand a distance great enough to cause this engagement between sleeve 31 and the valve stem 25, the handle portion 40 is rotated in a direction so as to retract the washer 43 from engagement with the sleeve 31. This will dispose the marker 53 from a position such that it may be viewed in plan view and will therefore indicate that the extensible automatic members are holding the valve 25 open. In the event that the burner 10 be extinguished, the rod 46 will cool which will cause retraction of the button 51 from engagement with the sleeve 31 which will permit disengagement of said sleeve from the valve stem 25 which will allow the spring 34 to close the valve. It is apparent that the valve may be closed manually by proper manipulation of the handle therefore. It is also apparent that by moving the sleeve 49 along the screw threads 48 the actuation of the button 51 may be controlled and varied.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In a controlling valve for gas burners and the like, a member having passages formed therein, a rotatable valve stem having a port therein adapted to establish communication between said passages, means for urging said valve stem from said communication establishing position, a sleeve disposed around said valve stem, a handle movably mounted in said valve stem and extending through a slot in said sleeve and adapted to engage said sleeve to hold said valve stem in said communicating position, and a thermically extensible member adapted to engage and force said sleeve into engagement with said valve stem to hold said stem in said 110

position when said handle is moved from engaging position.

2. In combination with a gas burner, a valve for controlling the gas supply thereto having an elongated stem, a sleeve disposed around said stem, and a thermically extensive rod extending across and anchored to said burner adapted to engage said sleeve and hold said stem in open position when said rod is heated, and manually adjustable means for holding said stem in open position, said means being adapted to be retracted from engaging position after said thermically operated means engages said sleeve.

15 3. In combination with a gas burner, a valve for controlling the gas supply thereto having an elongated stem, a sleeve disposed around said stem, and a thermically extensive rod extending across and anchored to said burner adapted to engage said sleeve and hold said stem in open position when said rod is heated, manually adjustable means for holding said stem in open position, said means being adapted to be retracted 20 from engaging position after said thermically operated means engages said sleeve, and means for indicating which of said holding 25 means is in operative position.

4. In combination with a gas burner, a valve controlling the supply of gas thereto, means urging said valve into closed position, manually operable means for opening said valve and retaining it in partially or fully open position, and heat responsive means 25 operable only upon release of said manually operable retaining means to retain the valve in its position while the burner is lighted and release it for closing by said first named means when the burner is extinguished.

40 In testimony whereof I affix my signature.

JOHN A. L. DETERS.
